UNITED STATES PATENT OFFICE.

BERNARD REBER, OF LOCLE, SWITZERLAND.

REPEATING-WATCH.

SPECIFICATION forming part of Letters Patent No. 447,973, dated March 10, 1891.

Application filed June 30, 1890. Serial No. 357,232. (No model.) Patented in Switzerland November 23, 1888, No. 102.

To all whom it may concern:

Be it known that I, BERNARD REBER, watch-manufacturer, of Locle, Switzerland, have invented new and useful Improvements in Repeating-Watches, (for which I have obtained Letters Patent in Switzerland November 23, 1888, No. 102,) of which the following is a specification.

The objects of my invention are as follows: first, to obtain a very smooth and easy movement of the lever which projects out of the watch-case and acts upon the repeating mechanism; second, to arrange such mechanism within less space, so as to be able to use larger wheels for the watch-movement in a given diameter of repeating-watches; third, to simplify the mechanism for the quarters. These three objects are effected by the devices of my improvement, which are shown in the accompanying drawings, wherein—

Figure 1 is a plan view complete of the repeating mechanism in large size. Fig. 2 is a plan view of the mechanism for operating the hammers; and Fig. 3 is a sectional elevation of the same. Figs. 4 and 5 are detached views showing the operation of the toothed plates separately and together, as will be more fully hereinafter set forth. Figs. 2 to 5, inclusive, are shown of exaggerated size.

In order that the drawings may easily be understood I have shown in the same only those parts to which the specification refers, the wheels driving the repeating mechanism and its speed-regulator being made as usual in repeating-watches, and not being necessary to readily understand the improvements claimed.

In my improvements the lever A has its pivot *a* near the center of the watch, and the end projects out of the case where it can be pushed by the finger in the direction indicated by an arrow. The lever C is pivoted to the lever A at *c*, and has a forked end bearing upon the pin *d* of the rack-lever D, which rack-lever D is pivoted at *d'* and carries an arm D', adapted to engage the hour-snail J'. A spring B, fixed to the plate bears upon a pin *b* upon the lever A to move the latter and the pivoted lever C back to their normal position. (Shown in Fig. 1.)

The rack-lever D acts, as usual, upon a pinion fixed to the spring-barrel axis E of the repeating mechanism, which carries the usual

hour-rack wheel F, acting upon the toothed plate *n* and the hour-hammer N.

In my improvements the hammers M and N are superposed and placed both upon the same axis, thus taking only half the space usually occupied.

In the enlarged view, Fig. 2, the parts are at rest. Fig. 4 represents the toothed plate *n* being operated for moving the hour-hammer N, and Fig. 5 represents both toothed plates *n* and *m* being operated to move both hammers.

Both hammers M and N are superposed and pivoted upon a common axle or stud K, (see Figs. 2 and 3,) and the toothed plates *n* *m* are also pivoted upon the same stud. The hammer N carries a pin *n*², acted upon by the toothed plate *n*, and the hammer M carries a pin *m*² acted upon by the toothed plate *m*, and the springs *n'* *m'* bear upon the pins *n*² *m*² to impart to the hammers the striking-blow in the return-movement.

The twelve teeth of the hour-rack F act upon the toothed plate *n*, which is in the same plane as these teeth, and the three teeth of the quarter-rack F' are wider than the teeth of rack F, and are the full depth of the spring-barrel and are in the plane of the teeth of both plates *n* and *m*, and these teeth act upon the toothed plates *m* and *n*. The points of the teeth of plates *m* *n* are of different lengths, so that one tooth is liberated by the teeth of F' slightly sooner than the other, thus causing the hammers to strike the well-known double stroke separately but close together, sounding the quarter-hours in double tune. The sounding of the quarters is regulated by means of the hook-arm G, pivoted to the lever H, and having a projection *g* acted upon by the spring J, which tends to bring the end of said lever H into contact with one of the steps of the usual quarter-snail I. A four-toothed rack f, affixed upon the wheel or rack F engages the hook-arm G into either its first, second, third, or fourth tooth, according to the one of the four positions in which said hook-arm G has been placed by the end of the lever H, bearing upon the snail I, nearly simultaneously with the rack-wheel F, being turned to its operative starting-point by a depression of the lever A, and before it returns under the action of the repeating

mainspring. The rack *f*, being thus hooked to the arm *G*, the latter will stop the rotation of wheel *F* as soon as the projection of the lever *H* bears against the screw-stop *h*.

5 The toothed plate *m* is maintained in the normal position shown in Figs. 1 and 2—that is to say, bearing against the pin *m*² of hammer *M*, by means of a spring *m*³. The toothed plate *n* is provided with a pin *o* bearing 10 against the toothed plate *m* by the joint action of the pin *n*² and spring *n'* when *n* is at rest, Figs. 1 and 2, and said plate *n* is also by the said spring *m*³ maintained in a normal position. When the toothed plate *n* is acted 15 upon by a tooth of wheel *F*, it acts upon said pin *n*² and causes the lifting of the hammer *N* without acting in any manner upon the toothed plate *m* or hammer *M*.

20 *P* is an adjustable pivoted stop-lever bearing at one end against the pin *m*³ for regulating the toothed plates *n* *m*, and the striking-hammers in the position into which the hammers are to be stopped to furnish a full stroke and clear sound. This is obtained by means 25 of the conical-ended screw *p* acting upon the other end of the lever *P*, and the partial rotation of this screw shifts said lever into the required position.

I claim as my invention—

30 1. In repeating-watches, the combination, with the lever *A*, having a pin *b*, and its pivot *a* near the center of the watch, of an arm *C*, pivoted to the lever *A* at *c* and having a forked lower end, the rack-lever *D* and its 35 pin *d*, against which the forked end of arm *c* bears, and a spring *B*, bearing against the pin *b*, substantially as and for the purpose specified.

2. In repeating-watches, the superposed hammers *M* and *N*, oscillating upon the same 40 pin or axis *K*, as set forth.

3. In repeating-watches, the combination, with the pin or axis *K*, of the superposed hammers *M* and *N* and the toothed plates *n* and *m*, all mounted and oscillating upon the 45 same axis, as set forth.

4. In repeating-watches, the combination, with the toothed spring-barrel and mechanism for imparting a partial rotation to the same in one direction, of the toothed rack *f*, 50 the hook-arm *G*, and its projection *g*, the spring *J*, the lever *H*, to which the arm *G* is pivoted, the snail *I*, and screw-stop *h*, adapted to engage and limit the movements of the lever *H*, substantially as set forth. 55

5. The combination, in repeating-watches, with the toothed spring-barrel and hammers, of a pivot or axis *K*, the toothed plates *n* *m*, the pins *n*², *m*², and *o* and springs *n'*, *m'*, and *m*³, and the regulating-lever *P*, substantially 60 as set forth.

6. In repeating-watches, the combination, with the superposed toothed plates *n* *m* and the hammers, of the spring-barrel having hour rack-teeth *F* on the plane only of one 65 toothed plate, and quarter-teeth *F'* upon the planes of both toothed plates *n* and *m*, substantially as set forth.

In testimony whereof I have signed my name to this specification in the presence of 70 two subscribing witnesses.

BERNARD REBER.
